UNITED STATES PATENT OFFICE.

GRAHAM D. TYSOR, OF SALEM, VIRGINIA, ASSIGNOR TO COMAS CIGARETTE MACHINE COMPANY, OF SALEM, VIRGINIA, A CORPORATION OF VIRGINIA.

CUTTING MECHANISM FOR CIGARETTE-MACHINES.

1,184,219.

Specification of Letters Patent. Patented May 23, 1916.

Application filed January 18, 1915. Serial No. 2,885.

To all whom it may concern:

Be it known that I, GRAHAM D. TYSOR, a citizen of the United States of America, and a resident of Salem, in the county of Roanoke and State of Virginia, have invented certain new and useful Improvements in Cutting Mechanism for Cigarette-Machines, of which the following is a specification.

10 This invention relates to improvements in cutting mechanism for cigarette machines and the object of the invention is to provide a machine of this character which will be durable and efficient in use and capable 15 of withstanding the hard use to which mechanisms of this kind are subjected.

The invention relates to a machine of the character shown in my application filed of even date herewith (January 18, 1915), Ser. 20 No. 2,884.

The invention consists in its preferable embodiment in the peculiar construction and arrangement of parts hereinafter described and then definitely claimed.

25 In the drawings accompanying and forming part hereof: Figure 1 is a side elevation of the end of a cigarette machine having my cutting mechanism secured thereto; Fig. 2 is a side elevation viewed from the opposite side to that shown in Fig. 1; Fig. 3 is an end elevation; Fig. 4 is a top plan view; Fig. 5 is a side elevation of the ledger plate and its parts in their normal positions; Fig. 6 is a perspective view of the same parts 30 when the ledger plate has been shoved downward by the cutter finding an obstruction in the cigarette rod; Figs. 7 and 8 are diagrammatic views of a modified form of the eccentrically arranged shafts; Fig. 9 is a 35 diagrammatic view of still another form of the eccentrically arranged shafts; Fig. 10 is a diagrammatic view showing the movement given to the cutter.

40 Referring now to the details of the drawings by numerals, 1 designates the end of the main frame or table of a cigarette machine, the machine proper not being illustrated and 2 designates the main drive shaft which not only is intended to operate all 45 the parts of the cigarette forming machine, but operates the cutting mechanism invented by me and illustrated in the drawings. This main drive shaft 2 is supported in suitable

bearings and through the worm gearing 4 and 5 is arranged to drive a gear 6 upon a supplemental shaft 7. This gear 6 meshes with and drives an idler 8 journaled upon a shaft 10 supported by bearings in an arm 12 adjustably held in position by means of a bolt 14 (see Fig. 1). This idler gear 8 drives the main gear 16 of my cutting mechanism and this gear 16 is adapted to drive all the other gears to operate the cutting mechanism. The main frame or table 1 has a supplemental table 18 adjustably secured thereto. This table may be held and adjusted in any desired way, but in my drawings I have disclosed the table as having a downwardly projecting standard 20 which fits within a vertical opening in the main frame or table 1 so that the table 18 may be adjusted vertically with respect to the table or frame 1. In order to provide for this adjustment, the standard 20 has a screw-threaded aperture within which fits an adjusting screw 22 to which is secured a worm gear 24 operated by a shaft 26 on the end of which is an adjusting bolt head 28. It follows from this construction that when the shaft 26 is rotated by a wrench being applied to the head 28, the shaft 22 may be rotated for the purpose of raising or lowering the table 18 with respect to the table 1.

25 The platform or table 18 is designed to support all the frame work and bearings for the different gears and shafts. To this platform or table 18 is secured, as by bolting or otherwise, two frames 30 and 32, the frame 30 being provided with three bearings 34, 35 and 36, while the frame 32 is provided with three bearings 37, 38 and 39. As will be seen from an inspection of Fig. 4, the bearings on the frame 30 are out of alinement with the bearings on the frame 32, for a purpose to be hereinafter described. 30 The bearings 34, 35 and 36 contain shafts 40, 41 and 42, the shafts 40 and 42 having gear wheels thereupon of equal size designated by the numerals 43 and 44, both of which mesh with the main gear 16 hereinbefore referred to (see Fig. 1). It follows from this construction that the shafts 40 and 42 will be driven at uniform speed. The shaft 41 has fixed to it a gear 45 which also meshes with and is driven from the gear 16. The bearings 37 and 39 contain shafts

46 and 47 which, as will be observed from Fig. 4, are out of alinement with the shafts 40 and 42. Likewise the bearing 38 contains a shaft 48 which is out of alinement 5 with the shaft 41. The shafts 40 and 46 have secured to their inner ends cranks 49 and 50 which in the embodiment illustrated are cross-heads and these are connected by a link 51, one end of which is pivotally connected to one cross-head 49 and the other end pivotally connected to the other cross-head 50. The shafts 42 and 47 have similar cranks or cross-heads 52 and 53 connected by a link 54 while the central shafts 41 and 48 also have similar cranks or cross-heads 56 and 57 connected by a link 58. The outer ends of the shafts 46 and 47 are provided with a pair of cranks 60 and 61 whose crank pins 62 and 63 (see Fig. 2) enter 10 bearings 64 and 65 in a horizontally reciprocable frame 66. This frame 66 has integrally secured thereto a pair of horizontal bearings 68 and 69 in which is journaled a sleeve 70 which is capable of rotation as well as longitudinal reciprocation in said 15 bearings 68 and 69. Within the sleeve 70 is journaled the cutter shaft 71 to one end of which is secured a rotary cutter 72 and to the opposite end of which is secured a 20 grooved pulley 73. A belt connects this grooved pulley with a similar pulley 74 supported upon a countershaft 75 journaled in a bearing 76 projecting upwardly from the bearing 34 hereinbefore described. 25 Upon the same shaft 75 which carries the pulley 74 is supported a third pulley 78 which is connected by a belt 79 with a drive pulley 80 fixed to the main or drive shaft 2. The result of this mechanism is that 30 the cutter shaft 71 and its rotary cutter 72 is rotated at a high speed through the belts and pulleys, during the time that the shaft 71 and its cutter 72 are moved back and forth in the bearings 68 and 69 in the manner 35 hereinafter described. To the outer end of the shaft 48 is secured a crank disk 81 whose crank pin 82 is connected by means of a link 83 with a head 84 clamped to the sleeve 70 already referred to as inclosing 40 the cutter shaft 71. The result of this construction is that when the shaft 48 and its crank disk 81 are rotated, the sleeve 70 and its shaft 71 will be given a longitudinal movement within the bearings 68 and 69 45 above referred to.

From the foregoing, it will be seen that the cranks 60 and 61 impart a circular movement to every part of the horizontal frame 66 which in effect causes an up and down 50 movement, and the crank disk 81 through the link 83 imparts a reciprocating movement to the sleeve 70 and its shaft 71 in the bearings carried by said frame so that the cutter 72 carried by the shaft 71 has both an up and down movement and a movement 55

longitudinal of its cutter shaft 71, these movements taking place simultaneously. These movements will be more fully referred to hereinafter.

The rotary cutter 72 is so placed that its cutting edge will rotate against a ledger plate 90, see Figs. 1 and 4. This ledger plate has the usual bell shaped mouth 92 for receiving the cigarette rod as it is continuously formed by the cigarette forming machine. It is the purpose of my invention to have this ledger plate and its bell shaped mouth 92, together with the rotary cutter 72, travel, in one direction, at as nearly the same speed as possible with the uniform speed of the continuously formed cigarette rod. Therefore the ledger plate 90 and its bell shaped mouth 92 must move back and forth upon the frame simultaneously with the rotary cutter 72. To accomplish this purpose I support the ledger plate upon a bracket 94 which is pivotally supported upon a rod 96 longitudinally slidable in bearings 97 and 98 formed on the upper ends of brackets 99 and 100 bolted to the main frame, see Fig. 2.

The bracket 94 which has been described as pivotally supported on the rod 96 moves with the rod 96 as the latter is moved longitudinally in its bearings 97 and 98. To give the rod 96 such a longitudinal movement, I secure to said rod a clamp 101 provided with an upwardly projecting arm 102 which is connected to a downwardly projecting arm 103 integrally secured to the aforesaid sleeve 70 by means of a clamp 104 (see Fig. 2). The said downwardly projecting arm 103 is slotted as shown at 105 and a screw passes through said slot and into the downwardly projecting arm 102 so that the arm 103 may move up and down with respect to the arm 102 simultaneously with the back and forth movement of the clamp 104 with its sleeve 70. The result of this construction is that when the frame 66 is given movement by the cranks 60 and 61 the slot 105 permits the arm 103 to move up and down with respect to the arm 102, and as the sleeve 70 is given a longitudinal movement in its bearings 68 and 69, a similar movement is given to the clamp 104 which therefore compels the arms 102 and 103 to have a similar back and forth movement. This back and forth movement of the arms 102 and 103 of course is imparted to the rod 106, for the arm 102 is secured to the rod 96 by means of the clamp 101; therefore the rod 96 has a similar longitudinal movement to the longitudinal movement of the sleeve 70 and as the ledger plate 90 with its bell shaped mouth 92 is supported by the rod 96, said ledger plate and its bell shaped mouth are compelled to travel back and forth with the rod 96 simultaneously with the back and forth travel of the sleeve 70 the cutter shaft 130

71 and the cutter 72. In order to prevent any serious injury should any wire or other foreign substance be accidentally formed into the cigarette rod, I have constructed 5 the ledger plate 94 so that it may "give" under undue strain. For this reason the bracket 94 is pivotally supported on the rod 96 as before described, and its construction is as follows: The ledger plate has been described as being connected to a bracket 94. This bracket 94 has secured to it an arm 110 which is the part referred to as pivotally supported on the rod 96. This arm 110 extends down a considerable distance below 15 the rod 96 and coacts with a stationary rod 112. To the arm 110 is pivotally connected a second arm 114 which extends down upon the opposite side of the stationary rod 112, the two arms 110 and 114 being connected by 20 a coil spring 115. This spring 115 normally holds the parts in the position shown in Fig. 5, but should there be any foreign substance within the cigarette rod, as for example a piece of wire, the moment the rotary cutter 25 strikes said foreign substance in the act of cutting, the whole ledger plate will be forced down against the tension of the spring 115, the arm 110 moving on the rod 96 thus separating the two arms 110 and 114 as indicated 30 in Fig. 6. As soon as the knife recedes as it is moved upwardly by the further operation of the machine, the spring 115 will draw the two arms 110 and 114 together and return the parts to normal position as shown in 35 Fig. 5.

I have hereinbefore referred to the fact that the shafts 40, 41 and 42 are eccentrically connected to the shafts 46, 47 and 48 by means of the pivoted links 51, 54 and 58. 40 The result of this peculiar connection is that the gear wheels 43 and 44 impart an irregular movement to the cranks 60 and 61 carried by the eccentrically arranged shafts 46 and 47, causing the cranks to have a 45 slower or retarded movement at one part of their rotation and an accelerated or faster movement at another part of their rotation. The retarded movement is during the time the cranks are moving the frame 66 upwardly and the accelerated movement is 50 while the cranks are causing said frame to lower the rotary cutter in the act of cutting the cigarette rod, or more accurately speaking, the rotary cutter is given a quick downward movement at the time the cigarette rod is being cut and while the knife is receding from the cut rod, but during all the rest of the upward movement and the corresponding downward movement, a slower 55 movement is imparted. And likewise, the eccentrically arranged shaft 48, connected by the link 58 with the shaft 41, causes an irregular movement to be given to the sleeve 70 and its cutter shaft 71. In other words, 60 the cutter shaft 71 with its sleeve 70 is

given an accelerated or more rapid movement when it is moving the cutter in the direction opposite to the movement of the cigarette rod, while a retarded or slower movement is given to the sleeve 70 and shaft 71 during the time the knife is traveling with the cigarette rod and the rod is being cut. By this means, I am enabled to provide a cutting mechanism wherein the rotary cutter, its ledger plate and the cigarette rod are traveling exactly at uniform speed with the cigarette rod and by which a quick dipping movement is given to the rotary cutter at the time the cigarette rod is being cut, and during this movement the ledger plate, while moving at the same speed as the cigarette rod, is traveling at a relatively slow speed compared with its movement during the time the cutter is not performing its cutting operation. 70 75 80 85 As soon as the cutter recedes from the cut rod its further upward movement and most of its downward movement is retarded by the eccentric connection, while on the return movement of the ledger plate, the sleeve 70 and the cutter shaft 71 is accelerated. The result of the two movements just described is a peculiar movement given to the cutter shaft and its cutter. Owing to the fact that the frame 66 90 95 is driven by the cranks 60 and 61, any given point on the said frame 66 will be given a complete rotary movement. But during this rotary movement to which each part of the frame 66 and its bearings 68 and 69 is 100 subjected, it must be remembered that the cutter shaft and its cutter are being moved longitudinally in said frame 66 and its bearings, and it must also be remembered that the rotary movement given to the frame 66 is accelerated, at one part of the 105 circular movement, and that the longitudinal movement given to the cutter shaft is also accelerated during one part of its movement. And it must also be remembered that 110 as the eccentricity of the central shafts is opposite to the eccentricity of the outside shafts the accelerated movement is given to the frame at a different time from that at which the accelerated movement is given 115 longitudinally of the cutter shaft. Hence, as stated, the resultant motion is peculiar. In Fig. 10 is illustrated a diagram to show the movement given to the rotary cutter. From this figure it will be seen that the 120 movement is substantially triangular with rounded corners. The actual cutting is done in that part of the triangle represented below the dotted line $a-a$ and it is during this part of the downward and upward movement of the cutter that the acceleration takes place. And during this period when the cutting is actually taking place, the cutter shaft and its cutter and the ledger plate are traveling at the retarded speed simul- 125 130

aneously with the movement of the cigarette rod, while during that part of the movement represented by the triangle above the line *a-a*, a retarded movement is given to the up and down motion of the cutter. It is during this retarded up and down movement, that the cutter shaft is moved longitudinally of its bearings in the opposite direction to the cigarette rod and it is during this return movement that the cutter shaft is given its accelerated movement above referred to.

I have hereinbefore referred to the fact that the table or frame 18 is adjustable with respect to the main table 1. This is for the purpose of permitting the table to be lowered by the adjustment of the bolt head 28 as the rotary cutter is reduced in diameter by its being periodically sharpened.

Instead of the cross-heads connected to the various eccentrically arranged shafts, I may use a pair of cranks as illustrated at 140 and 141 in Figs. 7 and 8 connected by a pivoted link 142, or I may use two disks 143 and 144 connected by a pivoted link 145. I regard each of these constructions, shown in Figs. 7, 8 and 9, as the equivalent of the construction shown in the other figures of my drawing.

In a companion application I have shown and broadly claimed a cutter having two shafts eccentrically arranged and connected by a pivoted link so that the cutter will be given a quick dipping movement, but in the present application this same mechanism is claimed in combination with a second eccentrically arranged shaft for giving a backward and forward movement to the cutter simultaneously with its quick downward movement.

Wherever in the following claims I have referred to two shafts eccentrically arranged I do not necessarily limit myself to an arrangement where there are two sets of shafts 40 and 42 and a third shaft 43 but intend the word two as broad enough to cover two shafts as well as two or more, the primary object being to provide means for giving the cutter shaft and ledger plate a movement parallel with the cigarette rod while at the same time another shaft is arranged to impart a movement to the cutter to and from the ledger plate and the cigarette rod passing through the same.

In illustrating my invention I have shown one embodiment thereof, but do not intend my claims to be limited to the construction shown as I desire to claim broadly a cutter combined with eccentrically arranged shafts whereby one shaft is employed to give the cutter shaft a longitudinal movement while another eccentrically arranged shaft is employed to give an up and down movement to the cutter, whereby the peculiar effect hereinbefore referred to is obtained.

Reference should therefore be made to the accompanying claims to determine the scope of my invention.

What I claim as my invention is:

1. In a device of the character described, a pair of shafts, crank pins operated by said shafts, a frame to which movement is given by said crank pins, a cutter shaft supported by said frame and moving therewith, and a shaft having a crank pin causing said cutter shaft to move longitudinally in its bearings as said frame is moved by the crank pins. 70 75

2. In a device of the character described, a pair of eccentrically arranged shafts, crank pins operated by said shafts, a frame to which movement is given by said crank pins, a cutter shaft supported by said frame and moving therewith, and a shaft having a crank pin causing said cutter shaft 80 85 to move longitudinally in its bearings as said frame is moved by its pins, said eccentrically arranged shafts causing the movement of said frame to be accelerated at one part of its movement. 90

3. In a device of the character described, a pair of eccentrically arranged shafts, crank pins operated by said shafts, a frame to which movement is given by said crank pins, a cutter shaft supported by said frame 95 and having movement therewith and capable of longitudinal movement with respect to said frame, and a pair of eccentrically arranged shafts having a crank pin causing said cutter shaft to move longitudinally in 100 its bearings as said frame is moved by its crank pins. 100

4. In a device of the character described, the combination of a cutter and cutter shaft, a frame for supporting said cutter shaft and permitting longitudinal movement of the shaft in said frame, a pair of eccentrically arranged shafts constructed to impart movement to said frame and said cutter shaft, and a pair of eccentrically arranged shafts constructed to move said cutter shaft longitudinally of the same in the aforesaid frame. 105 110

5. In a device of the character described, the combination of a cutter and cutter shaft, a frame for supporting said cutter shaft and permitting longitudinal movement of the shaft in said frame, a pair of eccentrically arranged shafts constructed to impart movement to said frame and said cutter shaft, a pair of eccentrically arranged shafts constructed to move said cutter shaft longitudinally of the same in the aforesaid frame, a ledger plate movable back and forth in the line of travel of the cigarette rod, and a telescopic connection between said ledger plate 115 120 and the cutter shaft whereby the longitudinal movement of the cutter shaft is imparted to said ledger plate. 125

6. In a device of the character described, the combination of a pair of shafts eccen- 130

trically arranged, a pivotally arranged link connection between said eccentrically arranged shafts, a frame, a crank connecting one of said shafts with said frame, whereby the rotary movement of said shafts is imparted to said frame, a cutter shaft supported by said frame and longitudinally movable therein, a shaft having a crank pin thereon for moving said shaft longitudinally in the frame, a ledger plate supported for longitudinal movement, and a telescopic connection between said ledger plate and said cutter shaft for moving the ledger plate and cutter shaft simultaneously in the line of travel of the cigarette rod.

7. In a device of the character described, the combination of a pair of shafts eccentrically arranged, a pivotally arranged link connection between said eccentrically arranged shafts, a frame, a crank connecting one of said shafts with said frame, whereby the rotary movement of said shafts is imparted to said frame, a cutter shaft supported by said frame and longitudinally movable therein, a pair of eccentrically arranged shafts, a pivoted link connection between said shafts, one of said shafts having a crank pin connecting it with the cutter shaft, whereby said eccentrically arranged shafts move said cutter shaft longitudinally, a ledger plate mounted for longitudinal movement in the line of travel of the cigarette rod, and a telescopic connection between said ledger plate and said cutter shaft, whereby the longitudinal movement of the cutter shaft is imparted to the ledger plate.

8. In a device of the character described, the combination of a cutter shaft, a sleeve surrounding said cutter shaft and permitting the cutter shaft to rotate therein, a frame having bearings for said sleeve and permitting said sleeve and its cutter shaft to move longitudinally in said bearings, a shaft having a crank pin thereon connected with said frame to move said frame and its sleeve and cutter shaft, and a shaft having a crank pin connected with said sleeve for moving the sleeve and cutter shaft in the bearings of said frame.

50 9. In a device of the character described, the combination of a cutter shaft, a sleeve surrounding said cutter shaft and permitting the cutter shaft to rotate therein, a frame having bearings for said sleeve and

permitting said sleeve and its cutter shaft to move longitudinally in said bearings, a shaft having a crank pin thereon connected with said frame to move said frame and its sleeve and cutter shaft, a shaft having a crank pin connected with said sleeve for moving the sleeve and cutter shaft in the bearings of said frame, and a ledger plate having a connection with said sleeve, whereby said ledger plate and said sleeve have the same longitudinal movement.

10. In a device of the character described, the combination of a cutter shaft, a sleeve surrounding said cutter shaft and permitting the cutter shaft to rotate therein, a frame having bearings for said sleeve and permitting said sleeve and its cutter shaft to move longitudinally in said bearings, a shaft having a crank pin thereon connected with said frame to move said frame and its sleeve and cutter shaft, a shaft having a crank pin connected with said sleeve for moving the sleeve and cutter shaft in the bearings of said frame, a ledger plate mounted for longitudinal movement, and a telescopic connection between the aforesaid sleeve and said ledger plate, whereby as said sleeve and its cutter shaft are moved longitudinally in the bearings of said frame the ledger plate is given simultaneous longitudinal movement.

11. In a device of the character described, the combination of a cutter shaft, a sleeve surrounding said cutter shaft and permitting the cutter shaft to rotate therein, a frame having bearings for said sleeve and permitting said sleeve and its cutter shaft to move longitudinally in said bearings, a pair of shafts eccentrically arranged having a crank pin connected with said frame to move said frame and its sleeve and cutter shaft, eccentrically arranged shafts having a crank pin connected with said sleeve for moving the sleeve and cutter shaft in the bearings of said frame, and a ledger plate having a connection with said sleeve whereby said ledger plate and said sleeve have the same longitudinal movement.

In testimony whereof I affix my signature in presence of two witnesses.

GRAHAM D. TYSOR.
